UNITED STATES PATENT OFFICE

2,466,160

HANDCART

Otto A. Deerrlamm, Glendale, N. Y.

Application May 12, 1948, Serial No. 26,539

2 Claims. (Cl. 280—51)

1

This invention relates to doll carts, and aims to provide certain new, useful and practical improvements therein whereby the utility and efficiency of the cart for carrying a doll or other article, thereby providing a very desirable practical toy for a child, are substantially enhanced.

Another object of the invention is the provision of a novel cart adapted to be pushed about by a child, with efficient means for holding a doll or other article in upright position therein.

The above broad as well as additional and more specific objects will become apparent in the following description, wherein characters of reference refer to like-numbered parts in the accompanying drawing. It is to be noted that the drawing is intended for the purpose of illustration only, and that it is neither desired nor intended to limit the invention necessarily to any or all of the exact details of construction shown except insofar as they may be deemed essential to the invention.

Referring briefly to the drawing, Fig. 1 is a front elevational view of the doll cart of this invention.

Fig. 2 is a side elevational view of the same.

Fig. 3 is a fragmentary sectional view taken on the line 3—3 of Fig. 2.

Fig. 4 is a fragmentary sectional view taken on the line 4—4 of Fig. 1.

Fig. 5 is a fragmentary sectional view taken on the line 5—5 of Fig. 2.

Fig. 6 is a fragmentary sectional view taken on the line 6—6 of Fig. 2.

Fig. 7 is a perspective view of a bracket per se used in constructing the cart.

Referring in detail to the drawing, the numeral 10 indicates a frame including the two longitudinal, substantially parallel side members 11, the upper cross-member 12 which also constitutes a handle for the cart, and the lower cross-member 13. An axle 14 is supported in the lower ends of the side members 11 and is provided with rubber-tired wheels 15.

Angle-shaped brackets 16 have one arm 17 secured against a frame member 11 just above the axle 14 and the other arm 18 extending inward at right angles to the arm 17, that is, the arms 18 extend toward each other and lie in a common plane. Supported on the bracket arms 18 is a forwardly extending floor 19. The brackets

2

16 are further provided with wings 20 extending upward from the arms 18 and in the same plane as the arm 17.

A substantially rectangular sheet of fabric such as, for example, canvas, has its lower edge secured against the front and side and rear edges of the floor 19, by any suitable means as, for example, nails 21, to form a bag 22 open at the top. The said lower edge of the bag 22 passes between the wings 20 and the edge of the floor 19. A rubber strip 23 is held by the nails 21 against the greater portion of the front and side edges of the floor 19.

A strap 24, formed of two strips 25 and 26, the latter having a buckle 27, is provided by securing the strips 25 and 26, as by nails 28 against the third cross-member 29 of the frame 10. The nails 28 also pierce the rear upper edge of the bag 22 and thus support the bag against the frame 10. A doll 30 may thus be carried within the bag 22 by strapping the doll against the rear of the bag, with the upper portion of its body exposed above the bag, as illustrated in Fig. 1. A peg 31 is provided midway of the front of the floor 19, whereby the cart may be stood in upright position in stable condition.

It is thus apparent that a very useful and practical toy cart has been provided, in which a child may wheel her doll. If the child possesses more than one doll, she may alternately secure one or another doll in the bag by means of the strap 24.

Obviously, modifications in form or structure may be made without departing from the spirit or scope of the invention.

I claim:

1. A cart comprising a frame including two longitudinal side members and a plurality of cross-members, one of said cross-members being positioned intermediate the length of said frame, angle-shaped brackets each having one arm secured to said side members near the lower ends of the latter and having the other arm of each extending toward each other in a common plane, a floor supported on said other arms and extending forward of said frame, a tubular-shaped bag having one peripheral edge thereof secured to the peripheral edge of said floor and having one side of the other peripheral edge thereof secured to said intermediate cross-member, a peg extend-

ing downward from said floor and positioned adjacent the front edge of the floor, and means for releasably securing an article such as, for example, a doll in said bag against the said one side of the other peripheral edge of the bag.

2. The cart set forth in claim 1, said other arms of said brackets having wings extending upward therefrom in the same plane as said one arm thereof and lying spaced from the side edges of said floor, opposed portions of said one peripheral edge of the bag lying between said side edges of the floor and said wings.
